UNITED STATES PATENT OFFICE.

JOHN MOFFAT, OF TORONTO, ONTARIO, CANADA.

SMOKE-CONSUMER.

1,332,914.

Specification of Letters Patent.

Patented Mar. 9, 1920.

Application filed August 12, 1918. Serial No. 249,539.

To all whom it may concern:

Be it known that I, JOHN MOFFAT, of the city of Toronto, in the county of York, in the Province of Ontario, Canada, have 5 invented certain new and useful Improvements in Smoke-Consumers, of which the following is the specification.

My invention relates to improvements in smoke consumers application for which was 10 filed in the United States Patent Office under Serial No. 203,947 on the 26th November, 1917, and the object of the present invention is to increase the calorific value of the products of combustion immediately 15 prior to their passage through the flues of the boiler.

My invention consists of a chamber located in the back wall of the furnace and provided with a spiral passage-way into the 20 center of which extends a conduit from the exterior of the furnace, the end of the spiral being provided with a conduit leading into the interior of the furnace at a point where the products of combustion turn 25 and pass upwardly into the flues of the boiler, the air being arranged to pass into the rear of the furnace space, and the parts being otherwise arranged and constructed in detail as hereinafter more particularly 30 explained.

Figure 1, is a sectional view showing the general arrangement and construction of my device when applied to a furnace of my type.

Fig. 2, is a perspective detail showing the form of the spiral chamber and the conduit leading into the center thereof.

Fig. 3, is a detail of the cover plate for the chamber showing the conduit, which 40 leads into the furnace itself.

In the drawings like characters of reference indicate corresponding parts in the various figures.

1 indicates a portion of a furnace having 45 a boiler 2 and a bridge wall 3 between the combustion chambers 4 and 5 the same as in my former application above referred to. 6 is the rear wall of the furnace and 7 is the space leading to a point at the back 50 of the boiler. The products of combustion pass through the combustion chambers 4 and 5 and up through the portion 7 back through the tubes of the boiler as indicated in the drawing.

In the rear wall 6 I place my device for 55 increasing the calorific value of the products of combustion. This device consists of a casing 8 provided with a spiral passage-way 9 formed by the spiral rib 10. The spiral passage-way at the center terminates 60 in a chamber 11 from which extends the conduit 12 at the outer end of which is located the slide damper 13.

The casing 8 is provided with a cover 8' having a conduit 14 preferably inclined and 65 leading into the chamber 5 at the lower end of the upper portion 7 thereof. The cover plate 8' is secured to the casing by means of the lugs 8³ and 8⁴ through which the bolts 8⁵ extend. The casing 8 is shown located in the wall 6 and the conduit 14 enters the furnace chamber 5 as indicated. The slide damper 13 is located outside of 70 the furnace.

By adjusting the slide damper the amount 75 of air admitted into the furnace chamber 5 may be regulated. The amount of adjustment will depend on the nature of the fire, which is passing through the combustion chamber 5.

The air that is admitted through the conduit 12 passes to the central portion of the casing 8 and then passes around the spiral to the wall 8² at which point it passes 80 through the conduit 14 into the furnace. 85

As the wall of the furnace is always warm the fresh air which passes through the conduit 12 and the casing 8 and the conduit 14 will have imparted to it a maximum amount 90 of heat before it reaches the furnace and such fresh air mixing with the products of combustion will on account of the value of the oxygen therein materially add to the calorific value of such products of combustion, and thereby effect economy in fuel as 95 well as also have a tendency to further reduce the amount of smoke produced in the furnace, and thereby eliminate to a great extent the smoke nuisance.

What I claim as my invention is:— 100

In a boiler furnace, the combination with the smoke chamber having the usual back wall, of a casing embedded in the wall below the flue level and having a spiral passage-way formed therein parallel to the inner face of the wall and in proximity thereto, a duct extending from the outer face of the wall to the central inner end of the pas- 105

sage-way, a valve at the outer end of the duct for controlling the air supply, and a duct leading from the outer end of the spiral passage-way at the perimeter of the 5 casing through the back wall of the smoke chamber and inclined downwardly so as to direct the heated air into the products of

combustion below and before they reach the flue.

JOHN MOFFAT.
